BOTTLE FITMENT

Edgeworth Greene, Upper Montclair, N. J.

Application November 30, 1935, Serial No. 52,300

15 Claims. (Cl. 215—22)

This invention in certain broader aspects relates to bottle closures of the type in which there is a cap overlying the mouth of the bottle and which must be ruptured in order that the bottle may be emptied.

More specifically, it relates to bottle closures of the type in which an orificed cover member overlies the top of the bottle and is held in position by means of a metallic ferrule that has a portion 10 interlocked with the cover member and a skirt portion spun around the neck of the bottle below the cover member, the orifice of the cover member being guarded by a cap which must be severed or torn apart in order to permit emptying of the 15 bottle. I have shown and described structures of this kind in my copending application for Letters Patent of the United States Serial No. 38,388, and the present invention comprises a carrying forward of what I there disclosed.

An object of the invention is to provide a cap overlying the discharge orifice or mouth of a bottle, and having a skirt portion, part of which is entered into and positively locked in the material of the bottle (or in a member that in effect forms 20 part of the bottle) so that after the cap is ruptured a tell-tale portion of it, difficult to eliminate, will remain in or associated with the bottle.

Another object of the present invention is to provide a structure involving the combination with 30 a cover member and ferrule assembly such as shown in the aforesaid application, of a cap member for closing the orifice of the cover, such cap member having a locked-in relation to the cover member, and the arrangement being preferably such that parts of the cap and parts of the ferrule are interlocked with each other, and the said 35 interlocked parts interengage with the cover member in such fashion that though the cap may be removed from the cover member to permit emp-

tying of the bottle, and though the ferrule may be 40 for the most part removed from around the bottle neck and from the cover member, those portions of the ferrule and cap member that have the locked-in relation with the cover member afore- 45 said will remain so securely held in the cover member that they will substantially resist efforts to remove them from such engagement with the cover, and in effect they will remain as a tell-tale and a discouragement to re-use of the cover 50 member. The invention in this aspect of it has special importance in cases where the cover member is part of an assembly applied to the bottle to render the same "non-refillable", though, as will appear, it has a use also where the non- 55 refillable features are not involved.

Another object of the invention is to provide a cap member which possesses features of construction that make it especially useful for combination with a bottle alone, or with a ferrule and a cover member in the aforementioned locked-in relation, but which possesses features that give it an importance of its own aside from such relationship; this cap is, as will be explained, of the rip type, so that it must be destroyed in order that the orifice of the cover member may be opened for 10 discharge of the bottle contents.

Other objects and advantages of the present invention will be apparent from the following description, when read in connection with the accompanying drawings, wherein:

Fig. 1 is a vertical section of a portion of a bottle neck with a stopper embodying the present invention applied thereto;

Fig. 2 is a fragmentary vertical section showing a ferrule and cap in pre-assembled relation to 20 each other and to the cover member of a bottle stopper, before they are permanently interlocked with said cover member; all of said elements being supported by or on a holder or anvil;

Fig. 3 is a fragmentary view similar to Fig. 1 25 showing the parts with the cap and ferrule interlocked with each other and locked into the cover member, but with non-refillable elements omitted;

Fig. 4 is a view similar to Fig. 1 illustrating a somewhat different form of cover member, cap 30 and ferrule;

Fig. 5 is a view similar to Fig. 3 showing the cover member, ferrule and cap as in Fig. 4, but without the valve casing and other parts of a non-refillable stopper combination shown in 35 Fig. 4.

Fig. 6 is an elevation of the guard member shown in Fig. 4;

Fig. 7 is a top plan view of the same;

Fig. 8 is a detail with parts broken away illustrating the assembly of the two-part cover member that appears in the previous figures;

Fig. 9 is an elevation of a form of cap utilizable as part of my invention, dotted lines indicating 45 the position of certain parts of the cap when the same has been ruptured;

Fig. 10 is a view similar to Fig. 9 showing the unruptured cap, the view being taken substantially at right angles to the Fig. 1 position;

Fig. 11 is a vertical sectional view taken on the line 11—11 of Fig. 12;

Fig. 12 is a plan view of the subject-matter of Fig. 10, and

Fig. 13 is a plan view showing the blank from 55

which is formed up the cap illustrated in Figs. 9 to 12 inclusive.

Referring to the numerals on the drawings, 14 indicates generally a portion of the neck of a bottle, such bottle neck having a shoulder 15 and a flange 16 spaced therefrom below the shoulder. The stopper secured to the bottle neck in this form of embodiment of the invention is made up of a valve casing 17 having a valve seat 18 surrounding the opening 19; a flat disc-like valve member 20 made of some suitable buoyant material, a weight 21, a guard member 22, a two-part cover member 23, and a ferrule 24. The valve casing, the valve member, the weight and the guard are constructed and related more or less in accordance with the teaching of my copending application Serial No. 8,605. Inasmuch as these parts have been described in detail and claimed in said application, further description thereof has been omitted herein. The valve casing 17 is provided with an annular flange 25 resting on top of a sealing gasket 26 which is positioned directly on the top of the bottle neck.

The orificed cover member is made up of a main portion 27 and a secondary ring portion 28. The main portion 27 has a tubular neck 29, the upper portion of the tube being externally threaded as at 30, and a body part 31, the top surface of which is stepped as shown at 32. Extending downwardly from the body part 31 are a number of spaced lugs 33 between which are arcuate shaped channels 34. The ring portion 28 has its lower surface stepped as indicated at 35 to engage the stepped upper surface of the member 31. This ring portion 28, however, does not completely engage the portions of the member 31, but is so shaped as to provide a substantially annular longitudinally extending narrow space 36 leading into a horizontal space 37. These two spaces form in effect an undercut slot extending completely around the cover member. The two parts 28 and 31 may be provided with registry means such as indicated at 38 in Fig. 8, such means serving to aid in assembling the two parts into a complete cover member and to assure that the parts will be registered properly.

If as is preferable the cover member is made of some frangible material, such as porcelain, etc., the two parts 28 and 31 may be permanently locked together during the firing of the device by applying a coating of glazing material between the contacting surfaces of these parts. This glazing material, when the cover member is fired, serves to bind the two component parts together and effectively unite them into a single member. Furthermore, the guard 22 may be permanently secured directly to the lugs 33 by applying a coating of glazing material between contacting parts of these respective members, so that the guard is secured to the cover member, also during the firing thereof. If the component parts of the cover member are made of other materials, various modes of fastening the two parts together can be used.

The ferrule 24 shown in Figs. 1 and 2 is composed of a skirt portion 39 (Fig. 2), a top part 40 shaped to conform to the top of the ring 28, and a depending annular flange 41 of such diameter as to be capable of freely entering the space 36 in the undercut slot. In the arrangement shown, the top part 40 is provided with a number of spaced openings 42 so situated therein as to extend into the vertical flange 41. Thus the top of this flange acquires a number of arcuate shaped depressions separated by narrow strips of mate-

rial, as and for the purposes explained in my copending application Serial No. 38,388.

The numeral 43 indicates a closure cap for the tubular part or spout of the cover member, this cap having a depending annular skirt 44, the lower end of the skirt being outwardly beaded as indicated at 45. The skirt portion of the cap is of a diameter to fit snugly within the flange 41 of the ferrule, with the bead 45 extending under the lower edge of the flange 41 when the parts are in the position shown in Fig. 2, where the concentrically arranged flange 41 and the lower part of the cap skirt are seen extending into the annular opening 36 of the cover member. In this figure the elements are shown supported by or on a tubular holder or anvil 70, which is so shaped that the top, (annular in form) serves as a table on which the bottom surface of the cover member 31 rests. The inner wall of the tubular holder or anvil 70 is provided with longitudinal grooves 71 in which the depending lugs 33 fit to restrain the cover member against rotation relative to the anvil during processing of the elements. If pressure be now exerted on the ferrule in the line of the depending flange 41 by a suitable tool, as explained in my copending application Serial No. 38,388, the cap and attached ferrule are brought to the position of Fig. 1, with the theretofore associated and contacting end portions of the cap-skirt and ferrule-flange forced laterally beyond the annular part 36 of the undercut slot. Since the inner wall of this portion is slightly inclined outwardly, and curved into the horizontal part 37, and since this inner wall is smooth or preferably glazed, in effect a die is formed, so that continued application of force results in the expansion of the associated parts of the ferrule and cap into the horizontal leg 37 of the slot, with the result that by the time the top of the ferrule is in contact with the top of ring 28, and the liner 44 of cap 43 is down in sealing relation with the top of the bottle, the associated parts of cap and ferrule are curled into the undercut part of the slot in the fashion indicated in Figs. 1 and 3.

The cap-skirt may be provided with an annular score or weakened line 46, located below the threads 30 and above the slot 36, and the skirt above this line 46 may be rolled into conforming engagement with threads 30. The engagement of the lugs 33 in the grooves 71 prevents rotation of the assembly during the rolling of threads in the cap-skirt. The score or weakened line 46 may be provided in the cap-skirt prior to or subsequent to the thread rolling operation as circumstances may dictate. As a result, if the cap be forcibly twisted in the unscrewing direction, a rupture will occur along the line 46, and the cap may be then backed off the threads 30 to permit pouring from the bottle; and of course the cap may thereafter be screwed on for temporary closure purposes.

In Fig. 3 the arrangement is similar to that shown in Fig. 1 with the exception that the non-refillable elements have been omitted; it being contemplated that a cover member for a bottle may be used without these elements. This arrangement serves as a very efficient cover for a bottle rendering tampering with the contents of a bottle prior to legitimate opening thereof readily discernible.

In the embodiment of Fig. 4 the structure differs from that of Fig. 1. The pouring nozzle is not externally threaded, nor is there a threaded cap. Instead, the cap 47 is of the "rip" type

shown in Figs. 9-13, and serves to hold in place, and protect against tampering, a cork 48. In this figure also, the ring 28 is provided with the annular series of projections 49 that extend through the several openings 42 of the ferrule, as and for the purpose explained in my copending application Serial No. 38,388.

Another difference in structure is found in the guard 50 of Fig. 4, and its relation to the cover member 31. Guard 50 (see Figs. 6 and 7) is provided with three laterally extending spaced lugs 51, shaped substantially as shown, that fit into corresponding recesses in the lower face of member 31, and are cemented therein by the application of glaze material and firing. Lugs 51 take the place of the lugs 33 of Fig. 1, and accordingly will have side surfaces to readily enter into and thereafter frictionally engage the inner wall of valve casing 17, in the manner set forth in my 20 U. S. Letters Patent No. 2,001,609.

Fig. 5 is like Fig. 4, but since it does not involve the "non-refillable" features there is no guard 50. This construction can be utilized in the same manner as that shown in Fig. 3, previously described.

I have referred to the cap 47 of Fig. 4, which is shown in detail in Figs. 9-13. This cap is made from a blank such as shown in Fig. 13, and comprises similar body portions 53 with an intermediate portion 54 between them defined by parallel spaced slits (or possibly weakened lines) 55; opposite symmetrically disposed flexible portions 56, and extensions 57 of the portions 56, the extensions 57 being joined to the portions 56 preferably by weakened lines 58. There are also two tear-off tabs 59 extending from the main body of the blank substantially in line with the median section 54, the root portions of these tear-off tabs 59 being separated from the adjacent sections 53 by means of notches 60. The blank of Fig. 13 is formed up so that the sections 53 and intermediate section 54 become the top and side walls of a cap, with the sections 56 and their extensions 57 bent sharply downward, the extreme ends of the extensions 57 bent up to form exterior hooks 61, the tear-off tabs 59 bent downward and the several parts being shaped to conform to the pouring nozzle over which the cap is to be positioned. In assembling, to form a unitary stopper for subsequent attachment to a bottle, the ferrule is slipped over the cap, somewhat as in Fig. 1, but instead of the end of the ferrule-flange 41 coming to rest against a cap-bead 45 as in that figure, the end of the flange is held in the cap-hooks 61. The assembly is now at the stage corresponding to Fig. 2, the cap and ferrule being positioned over the pouring nozzle of the cover member (the latter being supported on an anvil and having previously been fitted with the cork 48), and the interengaged portions of ferrule and cap pushed down by pressure on the flange, the latter carrying the cap portion with it and into the annular slot 36 and thereafter these parts are expanded and curled into the lateral extension 31 thereof. In order to open the bottle for pouring, one has only to take hold of one of the tear-off tabs 59 and pull upwardly and then across the top of the cap, thus approximately severing the cap into two parts, which may be easily torn off (Fig. 9, dotted lines), from those parts of the cap that are buried and remain in the undercut slot of the cover member. Access to the tear-off is made easy by the notches 60.

The cap is made of readily tearable sheet metal, 75 preferably aluminum about .008" thick, and the

metal of the ferrule in this as in every embodiment of the invention is of such gauge, (#26, when of aluminum) that when the interengaged parts of ferrule and cap are forced down into the slot of the cover member they cannot be removed therefrom without prohibitive difficulty, and remain as tell-tale and preventive of re-use of the cover member with a new cap and/or ferrule. The cap may be embossed or lithographed or the like so as to carry advertising matter; and it is contemplated that the cap may constitute a revenue or tax stamp, with text running from one end to the other of the longest dimension of the cap, and also possibly including the ferrule, such stamp being necessarily destroyed when the cap is ripped off in opening the bottle.

I have previously indicated and it will be understood that a cap like any of those shown may be entered into and positively held in substantially irremovable relation to a bottle at or adjacent its discharge orifice, without any interlocked or otherwise associated ferrule.

It is to be understood that the cap arrangement shown in Fig. 1 can be provided with hooks similar to those shown on the cap 47 instead of being provided at its lower edge with a bead. Furthermore, this cap 30 may have two depending finger portions similar to the depending portions of the cap 47. Also it is to be understood that a cover member attached to a bottle in the manner shown becomes in effect a part of the bottle, so that it may be said that the cap is anchored in a part of the bottle. The invention also contemplates that undercut slots may possibly be provided directly in the material of the bottle for the reception of the lower edge of a cap as shown.

From the foregoing it will be apparent that the present invention provides novel closure devices for bottles and for bottle cover members, which closure caps are so secured to the bottle or to a cover member that a part of the cap remains permanently engaged therewith. The invention is capable of modifications other than those shown in the drawings, in view of which any limitations imposed thereupon are to be such only as are set forth in the following claims.

I claim:

1. The combination with a bottle of an orificed cover member therefor provided with an annular slot in its outer surface, a ferrule for holding the cover member in place and having a flange entered into said slot, and a cap for the cover member having a skirt portion interengaged with that portion of the ferrule flange that is entered into said slot.

2. The combination of claim 1 in which the slot is undercut.

3. The combination of claim 1 in which the cap skirt is annular and exteriorly beaded at its lower end, and in which the lower end of the ferrule flange cooperates with the said bead.

4. The combination of claim 1, in which cap skirt portions are provided with exterior end hooks and the lower end of the ferrule flange is engaged in the hooks.

5. A preliminarily assembled bottle fitment comprising an orificed cover member having a slot therein and a closure cap for the orifice in said cover member, said cap having a portion thereof locked in said slot and having another portion separable from the locked-in portion to uncover said orifice.

6. A preliminarily assembled bottle fitment comprising an orificed cover member having an

undercut slot therein and a closure cap for the orifice in said cover member, said cap having a portion thereof locked in said slot and having another portion separable from the locked-in portion to uncover said orifice.

7. A preliminarily assembled bottle fitment comprising an orificed cover member having an annular undercut slot therein and a closure cap for the orifice in said cover member, said cap having an annular skirt portion thereof locked in said slot and having another portion separable from the locked-in portion to uncover said orifice.

8. A preliminarily assembled bottle fitment comprising an orificed cover member having an undercut slot therein and a closure cap for the orifice in said cover member, said cap having depending skirt portions thereof locked in said slot and having another portion separable from the locked-in portions to uncover said orifice.

9. A preliminarily assembled bottle fitment comprising an orificed cover member having an annular undercut slot therein, an attachment ferrule having a skirt portion and an annular depending flange portion, and a closure cap for the orifice in said cover member, said cap having an annular skirt portion, the depending flange portion of said ferrule and the annular skirt portion of said cap being locked in said undercut slot, said cap having another portion separable from the locked-in skirt portion.

10. A preliminarily assembled bottle fitment comprising an orificed cover member having an annular undercut slot therein, an attachment ferrule having a skirt portion and an annular depending flange portion, and a closure cap for the orifice in said cover member, said cap having depending skirt portions, the depending flange portion of said ferrule and the depending skirt portions of said cap being locked in said undercut slot, said cap having another portion separable from the locked-in skirt portions.

11. A preliminarily assembled bottle fitment comprising an orificed cover member having an

annular undercut slot therein, an attachment ferrule having a skirt portion and an annular depending flange portion, and a closure cap for the orifice in said cover member, said cap having an annular skirt portion, with an external bead 5 at the bottom thereof, the depending flange portion of said ferrule and the annular skirt portion of said cap being locked in said undercut slot with the lower edge of the ferrule flange engaging said bead, said cap having another portion separable from the locked-in skirt portion.

12. A preliminarily assembled bottle fitment comprising an orificed cover member having an annular undercut slot therein, an attachment ferrule having a skirt portion and an annular depending flange portion, and a closure cap for the orifice in said cover member, said cap having depending skirt portions, external hooks formed at the lower edges of said skirt portions, the depending flange portion of said ferrule and the skirt portions of said cap being locked in said undercut slot with the lower edge of the ferrule flange fitting in said hooks, said cap having another portion separable from the locked-in skirt portions.

13. A cap of the kind described comprising a generally inverted cup shaped member having weakened lines in the top thereof defining a zone extending diametrically across the top of the cup, oppositely disposed tear-off tabs extending downwardly from the top of said member in line with said zone, and oppositely disposed side-wall extensions extending below the ends of said tabs on opposite sides of said zone, each extension being provided with a transverse weakened line 30 above its lower end.

14. The device of claim 13 in which the longitudinal edges of the tear-off tabs and of the extensions are spaced apart.

15. The device of claim 13 in which the lower 40 ends of said extensions are turned upwardly to form external pockets.

EDGEWORTH GREENE.
